(No Model.)

C. B. ANDERSON.

FIRE ESCAPE.

No. 310,014.

Patented Dec. 30, 1884.

UNITED STATES PATENT OFFICE.

CHARLES BINGLEY ANDERSON, OF MAYSVILLE, KENTUCKY.

FIRE-ESCAPE.

SPECIFICATION forming part of Letters Patent No. 310,014, dated December 30, 1884.

Application filed July 12, 1884. (No model.)

To all whom it may concern:

Be it known that I, CHARLES B. ANDERSON, a citizen of the United States, residing at Maysville, in the county of Mason and State of Kentucky, have invented certain new and useful Improvements in Fire-Escapes; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a side view of my device. Figs. 2 and 3 are edge views of the same, and Fig. 4 is a vertical sectional view.

This invention, which is an improvement on a patent granted to me and numbered 296,502, relates to that class of fire-escapes in which the lowering-cord is attached to a crank-shaft turning between disks, the support for the person descending being connected therewith by proper means; and it consists in the two following features: an improved method of securing the crank-handles to the rotating shaft and of increasing and decreasing their acting lengths, and an improved method of attaching the locking-cord to the device.

It consists, further, in certain details of construction hereinafter more fully described.

In the drawings, A A represent two equal parallel and similar disks of iron or other suitable material, joined together near their edges by a ring of metal, a , so as to form a box. a' is a transverse slit or opening in said ring a , within which, near its opposite edges, are the transverse rollers a^2 a^3 , which have their bearings in the disks A A, near the edges of the same. If desired, the disks A A may be united by equal and similar rods, a^3 a^3 , riveted to them at proper points around their edges, in lieu of the ring a .

B is a hollow shaft, of iron or other proper material, turning centrally and transversely in proper openings in the disks A A, and having the similar ends, b b' , projecting outward from the disks; and b' b' are two similar slots in each end b , which slots run at right angles to the axis of the shaft B, and are diametrically opposite to each other, and each slot in one

end is longitudinally opposite one of the slots in the other end.

C are two equal and similar crank-levers, provided with the handles c c , rotating in the usual manner, and preferably united by a hinge-joint to the arms of the lever, so as to be turned down when not in use.

c' is the arm of each lever, with its inner end engaging in and passing through the slots b' b' at one end of the shaft B, where it is secured by the pin c^2 in its extreme end, which bears against the side of the shaft B, opposite the handle c , and by the longitudinal spring c^3 , which is pivoted at its center to the outer surface of the arm, and has the end of its inner leaf bearing against the side of the shaft B directed toward the handle c .

When it is desired to bring the handle nearer the shaft B, (i. e., shorten the crank-lever,) the said inner leaf is depressed and the arm c' slid in the slots b' b' until both leaves of the spring c^3 bear against the inner sides of the shaft, the spring being just sufficiently long for that purpose. As the slots b' b' on both sides of the shaft are longitudinally opposite each other, the crank-handles, when inserted, may stand parallel or diametrically opposite each other, so that a person can turn them hand over hand or both hands together, as most convenient. If desired, an additional spring, c^4 , may be added, which, when the crank-lever is out to its fullest extent, will rest inside the end of the shaft B and have its end bearing against the inner surface of the same.

D is the escape rope or wire, attached above to some proper point, and having its lower end, which passes between the rollers a^2 a^3 , fixed to and rolled upon the shaft B between the disks A. The said escape-rope is preferably made in the form of a metal tape, which will wind closer in the shaft B and allow the disks and the levers to be made smaller. In this case the disks are closed by the ring a , and the device resembles in shape a tape-measure. (When a rope or wire is used, the disks are connected by the rods.) The escape-rope has secured to it at its upper end the hook d , closed by a spring or spring-point, so as to form a snap-hook, for a purpose hereinafter mentioned.

d' is a grapple similar to that in my Patent No. 296,502, which, when necessary, can be attached to the snap-hook *d*. The said snap-hook is preferably similar to that in the patent issued to me and numbered 296,502.

E is a semicircular piece of plate-iron or other suitable material, pivoting transversely in the disks *A A*, near their edges, at a point diametrically opposite to the rollers *a² a²*. The piece *E* is provided with a hole, *e*, for the engagement of a snap-hook, *e'*, to which is properly attached a band or belt, *e²*, being similar to those in my Patent No. 296,502.

F is the releasing-cord, having a ring at its upper end, which engages the snap-hook *d* in the usual manner, and thence passes through an opening, *f*, in a piece of metal, *f'*, similar to *E*, and pivoted to the edges of the disk near the rollers *a² a²*, on the side to which the back of the hook turns. The releasing-cord *F* is tied in a slip-knot in the opening *a'*, and has its lower part hanging down within reach of a person attached to the device, so that by pulling on it he can untie the knot and release the device to permit it to descend.

The device being wound up, and attached by securing the snap-hook *d* over any proper object on the window-frame or inside the room, or, if no such object exists, by fixing the grapple *d'* to any proper point, with the releasing-cord tied in the opening *a'*, so that the device will not unwind, the person who wishes to descend attaches himself to the latter by the snap-hook on one end of belt *e²*, which is to

pass around the body under the arms, (the snap-hook passing through the ring on the opposite end of the belt and then engaging the opening in the piece *E*.) When attached he puts himself outside the window, and then, having jerked the releasing-cord so that it will untie, regulates his descent or brings himself to a stop by means of the crank-handles.

Having thus described my invention, what I claim as new, and desire to secure by Letters Patent, is—

1. In a fire-escape, the combination, with the disks *A A*, properly joined together, and provided with the rollers *a² a²* and piece *E*, and the hollow shaft *B*, provided at each end with the slots *b' b'*, of escape-rope *D*, of metal tape, and properly joined to the shaft *B*, and the crank-levers *C C*, composed of the handles *c c* and arms *c' c'*, and provided with the pin *c²* and springs *c³ c⁴*, substantially as specified.

2. In a fire-escape, the combination, with the shaft *B*, crank-levers *C C*, and disks *A A*, provided with the pieces *E* and *f'*, of the escape-rope *D*, properly secured to the shaft, the releasing-cord *F*, and hook *d*, provided with the proper closing-point, substantially as specified.

In testimony whereof I affix my signature in presence of two witnesses.

CHARLES BINGLEY ANDERSON.

Witnesses:

CASPER HEEG,
CHARLES ED. LORD.
